(57) **CLAIM**

The ornamental design for a Wifi borescope inspection camera, as shown and described.

DESCRIPTION

FIG. 1 is a top perspective view of a Wifi borescope inspection camera showing my new design;

FIG. 2 is a front view of the Wifi borescope inspection camera;

FIG. 3 is a rear view of the Wifi borescope inspection camera;

FIG. 4 is a right view of the Wifi borescope inspection camera;

FIG. 5 is a left view of the Wifi borescope inspection camera;

FIG. 6 is a top view of the Wifi borescope inspection camera;

FIG. 7 is a bottom view of the Wifi borescope inspection camera; and,

FIG. 8 is a bottom perspective view of the Wifi borescope inspection camera.

The broken lines depict portions of the Wifi borescope inspection camera in which the design is embodied that form no part of the claimed design. Additionally, the separations on the cable in FIG. 1 indicate break lines for indeterminate length. Any portion of the article between the break lines form no part of the claimed design.

1 Claim, 8 Drawing Sheets
